(57) **CLAIM**

The ornamental design for a heat gun for snow and ice, as shown and described.

DESCRIPTION

FIG. 1 is a side view of a heat gun for snow and ice showing my new design;

FIG. 2 is another side view thereof;

FIG. 3 is a back view thereof;

FIG. 4 is a front view thereof;

FIG. 5 is a top view thereof; and,

FIG. 6 is a bottom view thereof.

The broken lines in FIG. 4 illustrate features of the heat gun for snow and ice that form no part of the claim.
